UNITED STATES PATENT OFFICE.

EMMANUEL T. RICHERT, OF AKRON, OHIO.

DESIGN FOR A TOY SPOTTED BALLOON.

60,814.

Specification for Design. Patented Apr. 11, 1922.

Application filed October 27, 1921. Serial No. 510,970. Term of patent 14 years.

To all whom it may concern:

Be it known that I, EMMANUEL T. RICHERT, a citizen of the United States, residing at Akron, in the county of Summit and State of Ohio, have invented a new, original, and ornamental Design for a Toy Spotted Balloon, of which the following is a specification, reference being had to the accompanying drawing, forming part thereof.

Fig. 1 is an enlarged elevation of the balloon in a condition ready to be inflated.

Fig. 2 is a bottom plan view of the same.

I claim:

The ornamental design for a toy spotted balloon as shown.

EMMANUEL T. RICHERT.
